ELECTRIC ATTACHMENT PLUG

Max Polis, Brooklyn, N. Y., assignor to Sylvia G.
Polis, Brooklyn, N. Y.

Application September 24, 1938, Serial No. 231,490

3 Claims. (Cl. 173—330)

My invention relates to electric attachment plugs, which are adapted to engage with the standard types of receptacles on the market and more particularly to such receptacles when installed in more or less inaccessible locations, as for example, when installed in the lower part of the room or in the sub-base moulding of the same.

One object of my invention is to provide an attachment plug which can be easily and cheaply manufactured, so that it will not cost more than the usual well known plugs of its type.

The principal object of my invention is to provide an attachment plug which can be inserted in the receptacle with the greatest facility and especially where it may not be possible to see the receptacle while the plug is being inserted.

Referring to the drawing:

Fig. 1 is a top view of two receptacles showing my attachment plug about to be engaged with one of the same.

Fig. 2 is a side view of my attachment plug and a sectional view of the receptacle through 2—2 in Fig. 1 looking from the left.

Fig. 3 is a side view of my attachment plug.

Fig. 4 is a bottom view of my attachment plug.

Fig. 5 is an enlarged view of the present standard type of attachment plug terminal.

Fig. 6 is an enlarged form of my attachment plug terminal.

Fig. 7 is another enlarged form of my attachment plug terminal.

Fig. 8 is another enlarged form of my attachment plug terminal.

Fig. 9 is an enlarged side view of all forms of my attachment plug terminal.

In Figs. 5, 6, 7 and 8, a sectional view of the receptacle orifice is shown as in Fig. 2 only enlarged.

Similar numerals refer to similar parts throughout the several views.

One form of receptacle, with which my attachment plug engages, included a casing 2, within which the receptacle contacts are mounted in any usual well known manner. Each receptacle is provided on its outer surface with a depression constituted by four inclined planes 4 and terminating in an orifice 16. These orifices 16 are rectangular in form, the long side being several

times longer than the width. In the type of receptacle shown a face plate of attractive appearance is generally used to provide a covering for the space between the face of the receptacle and the wall or sub-base upon which it is mounted.

Referring now to the various features of my invention, which are most easily seen in Figs. 2—3—6—7 and 8, the base of my plug is similar to the well known types consisting usually of a moulded member 3, having a recess on the under side in which the electric contacts 13 are mounted. These contacts 13 are supplied with large headed screws 14, by means of which the electric conductors to be connected to the receptacle are secured to the contacts. Mounted perpendicularly on each contact 13 is a rectangular contact member 5 usually bent up from the material of which the contact 13 is constructed. In the ordinary form of plug there are two such contact members 5, of rectangular cross section, spaced from each other the same distance as the orifices 16 of the receptacle 2, and with their wide sides parallel with each other. Manifestly however, my invention is not limited to a plug having two contact members as it can be embodied in a plug having any number thereof.

The free end of my contact member 5 terminates in an extension 8, of less width than the contact member 5, and also of less width than the width of the receptacle orifice 16. This extension 8 need be of only short length as shown best, as to proportions, in one form in Fig. 3. The hole 17 shown in the contact member 5 is no part of the present invention and is used to engage with the receptacle parts in a well known manner.

Between the extension 8 and the contact member 5 I may use an inclined portion 9 as shown in 3 and 6 or I may use a curved fillet 12 as shown in Fig. 8. The outer end 7 of the extension 8 may be flat as in Figs. 3 and 6 or rounded as in Fig. 8.

In Fig. 7 I show a modified form of my invention wherein I make the extension 8 by means of chamfering the sides thereof as at 11, so that the free end of the contact member 5 is small enough to partly enter the orifice 16 perpendicularly to its major dimension. In Fig. 5 is shown the present form of contact member 5 which obviously cannot enter the orifice 16 of the receptacle unless it is in its operative position, that is, in parallel juxtaposition therewith.

It is seen that the free end 8 in all forms of my invention can enter the orifices 16 no matter in what relation they are brought together, so that once engaged, it is only necessary to turn 50 the plug around the engaged contact member 5, as a fulcrum, until, as in the case of a plug having two contact members 5, both contact members 5 are in the proper position to enter their respective orifices 16 of the 55

receptacle. This feature is shown in Figs. 1 and 2 wherein one of the extensions 8 of the contact members 5 is engaged with one of the receptacle orifices 16 when in an inoperative relation therewith, now by simply rotating the plug around the engaged contact member 5, and following the arc 15, (drawn around the engaged member 5 as a center) the plug may be brought into operative relation with the receptacle and inserted in the receptacle with the greatest facility. It should be noted that the plug may be rotated into operative relation with the receptacle in either direction to accomplish the desired result.

It is obvious that many forms of extensions 8 may be devised without departing from the spirit or scope of my invention and having shown and described the same so that anyone, skilled in the art to which it pertains, can make the same, what I claim as my invention and desire to cover by Letters Patent is—

1. The combination, with a receptacle having rectangular orifices of long and short dimensions, of a plug having rectangular electric contacts secured thereto having greater width than thickness, effective, when the width thereof is parallel with the long dimension of the orifices, to enter the same, and rectangular projections extending from the ends of said contacts of less width than the contact and also the short dimension of said

orifices and effective to enter the orifice in all positions, with reference thereto, to form a pivotal connection therewith to guide the plug into operative juxtaposition with said receptacle.

2. The combination, with a receptacle having 5 rectangular orifices of long and short dimensions, of a plug including electric contacts having greater width than thickness, and effective to enter said orifices, and projections extending from the ends of the contacts of less width than 10 the contacts and also the short dimension of said orifices and effective when entered therein in inoperative juxtaposition with said receptacle to form a pivotal connection to guide the plug into operative relation with the receptacle. 15

3. The combination, with a receptacle having rectangular orifices with long and short dimensions of a plug including rectangular electric contacts, effective to enter said orifices, when the plug is in operative juxtaposition therewith, projecting members extending from the ends of said contacts, of less width than the short dimension of the orifices, and shoulders formed by the members and said contacts, effective to bear against the face of the receptacle, when a member has 20 entered an orifice and the plug is thereby not in operative position therewith, to form a pivotal connection to guide the plug into said position. 25

MAX POLIS.
